INVENTOR
FREDERICK L. KUNKEL

BY *Reinhart & Sonn.*

ATTORNEY

UNITED STATES PATENT OFFICE.

FREDERICK L. KUNKEL, OF MILWAUKEE, WISCONSIN.

FABRIC.

Application filed April 9, 1926. Serial No. 100,876.

This invention relates to wire fabrics and more particularly to fabrics serving as supports for bedding placed thereon.

One object of the present invention is to simplify and improve the construction of fabrics of the character mentioned.

Another object of the present invention is to provide improved securing means for effectively connecting the elements constituting the fabric.

A further object is to provide a fabric which is readily yieldable both longitudinally and transversely to sustain and accommodate with comfort an individual resting thereon, thereby contributing to its durability and wearing qualities.

A still further object is to provide means for selectively limiting the maximum transverse spread of the fabric within the elastic limits of the yielding means.

Other objects and advantages will appear from the following description of an illustrative embodiment of the present invention.

In the drawings:

Fig. 1 is a plan view showing a fabric embodying features of the present invention;

Fig. 2 is a sectional view taken substantially along line 2-2 of Fig. 1; and

Fig. 3 is a sectional view taken substantially along line 3-3 of Fig. 1.

The fabric selected for illustration is, in this instance, suspended from the ordinary frame having the horizontal flanges 10 thereof provided with a series of spaced apertures 11 for the reception of the usual series of helical springs 12, which furnish the desired longitudinal resiliency and elasticity.

The fabric itself, in which the novel features of the present invention more particularly reside, constitutes a series or plurality of spaced straps 13 resiliently suspended from the frame 10 by means of the helical springs 12 which are interposed between the apertured extremities thereof and the frame 10 in any appropriate manner such as by anchoring the hooked ends of the springs in the aligned apertures 11 and 14 of the frame and straps, respectively. To resiliently maintain the straps 13 in spaced relation, a

transverse series of resilient members, in this instance helical springs 15, are suspended between the side straps 16 which are preferably somewhat wider than the straps 13. As shown, the springs 15 are each secured at

their ends in a manner to be hereinafter described, to the members 16 and also to each intermediate strap 13 to prevent irregular shifting of the straps and to resiliently sustain them intermediate their ends.

The novel means for resiliently sustaining the straps consists in providing each strap, which is preferably of flexible metal, with a plurality of inclined slots 17, in this instance two, at spaced intervals to receive and accommodate a corresponding number of convolutions of the springs 15, which project therethru. To retain the convolutions of the spring in the slots 17, a transverse tension member 18, preferably a wire, is interposed between the straps 13 and the projecting convolutions of the springs 15, as clearly shown in Fig. 2, so that the springs 15 are retained in proper position at all times. The wire 18, as shown, has bent terminals 19 to restrain the movement within predetermined limits, however, the springs 15 are active transversely and are limited only when the transverse spread is sufficient to have the ends 19 of the wire engage the ends of the springs through which the wire 18 extends. It is to be noted that the wire 18 helps to sustain the load on the fabric, but does not render the springs 15 inactive until the transverse spread has reached a maximum as defined by the length of the wire 18.

With the arrangement above described, the fabric is readily assembled, since the transverse springs 15 may be extended end to end and anchored after which spaced convolutions thereof are projected through the slots in the intermediate members 13. The wire is then inserted within the spring, intermediate the projected convolutions and the underside of the straps, and the ends thereof are bent as at 19 to limit the maximum transverse spread of the fabric.

Various changes may be made in the embodiment of the invention hereinabove specifically described, without departing from or sacrificing any of the advantages of the invention as defined in the appended claims.

I claim:

1. A bed-bottom fabric comprising a series of longitudinal load-sustaining straps, transverse helical springs intersecting said straps, said straps having diagonal slots formed therein for receiving convolutions of said

springs, and a wire projected lengthwise through each spring for retaining said convolutions within said slots.

2. A bed-bottom fabric comprising a series of longitudinal load-sustaining straps each having a plurality of diagonal slots, a plurality of transverse helical springs superimposed upon said straps with convolutions

thereof projected through said slots, and a wire projected lengthwise through each spring beneath said straps to retain said projected convolutions within said slots. ¹⁰

In witness whereof, I hereunto subscribe my name this 3d day of April, 1926.

FREDERICK L. KUNKEL.
